UNITED STATES PATENT OFFICE.

FRANK VAN DER CRUYSSSEN, OF WEBSTER GROVES, MISSOURI.

PISTON PACKING-RING.

1,089,026.

Specification of Letters Patent. Patented Mar. 3, 1914.

Application filed May 26, 1913. Serial No. 769,931.

To all whom it may concern:

Be it known that I, FRANK VAN DER CRUYSSSEN, a citizen of the United States, residing at Webster Groves, Missouri, have 5 invented a certain new and useful Improvement in Piston Packing-Rings, of which the following is a full, clear, and exact description, such as will enable others skilled in the art to which it appertains to make and 10 use the same.

This invention relates to piston packing rings, and particularly to piston rings of the type that are used in internal combustion engines.

15 One object of my invention is to provide a leak-proof piston ring that can be manufactured at a low cost and which is so designed that one ring will pack the piston of an internal combustion engine as effectively as three or four rings of the type now 20 generally used, thereby effecting a great saving in the manufacture of internal combustion engines and also reducing the number of parts of same.

25 Another object is to provide a piston ring which is so designed that the parts of same cannot separate and thus permit the operating medium in the cylinder to leak around the ring in case the groove in the piston 30 that receives the ring is wide enough to permit the ring to move longitudinally of the piston. And still another object is to provide a ring that can be applied and removed easily and which is so designed that 35 it will remain leak-proof even after the parts of same have worn excessively.

Other objects and desirable features of my invention will be hereinafter pointed out.

40 Figure 1 is a vertical sectional view of the cylinder of an internal combustion engine showing the piston in elevation and equipped with a packing ring constructed in accordance with my invention; Fig. 2 is 45 a perspective view of said packing ring; Fig. 3 is a perspective view of the body portion or channel-shaped section of the ring; Fig. 4 is a perspective view of the intermediate section that is arranged between the flanges of the body portion of 50 the ring; Fig. 5 is a cross sectional view of the ring taken on the line 5-5 of Fig. 2; and Fig. 6 is a cross sectional view taken on the line 6-6 of Fig. 2.

55 Referring to the drawings which illus-

trate the preferred form of my invention, A and B designate two split ring shaped expansible members combined in such a manner that each member extends across the joint between the ends of the other member. 60 The member A which I will term the body portion or section of the ring, is channel-shape in cross section, and comprises a pair of horizontally disposed flanges 1 and 1^a that project laterally from a vertically disposed web 2. The member A is ring-shaped and is split at one point, as shown in Fig. 3, so that it can expand and contract, and the end portions of said member are so shaped that they lap over each other. In the preferred form of my invention, as herein 70 shown, the upper half of the web 2 at one end of the member A is notched out and the top flange 1 is cut off, and the lower half of the web at the opposite end of said member is notched out and the bottom flange 1^a is cut off so as to form a scarf-joint in the member A. By splitting the member A in this manner I obtain a projection 3 at one end of said member that laps over a 80 projection 4 at the opposite end of said member, as shown in Fig. 3, the top flange 1 of the member A extending clear to the end of the projection 3 and the bottom flange 1^a of said member extending clear to the end 85 of the projection 4.

The space or joint in the vertical web and flanges of the member A is covered by the member B or intermediate section of the ring. This intermediate section B consists 90 of a split expansion ring of rectangular-shape in cross section whose depth corresponds to the vertical distance between the horizontally disposed flanges of the member A and whose width preferably corresponds 95 to the length of said flanges. The member B surrounds the vertical web 2 of the member A and lies snugly between the horizontal flanges of said member, as shown in Fig. 5, said member B being so arranged that the joint between the ends of same lies diametrically opposite the joint between the ends of the member A. The end portions of the member B are also preferably notched out so as to form a scarf-joint comprising overlapping portions, as 100 shown in Fig. 4. Means is provided for preventing the intermediate section B from moving circumferentially with relation to the body portion A of the ring or from as- 105 110

suming such a position that the joint in the member B lines up with the joint in the member A. The means herein shown for accomplishing this consists of a pin 5 on the member A that projects outwardly from the vertical web of said member, as shown in Figs. 2 and 6, so as to form a stop against which one end of the intermediate section B bears, the end of the member B being provided with a notch or recess 6, as shown in Fig. 4, for receiving said pin.

The ring, composed of the two expansible members A and B, is arranged in the usual manner in a horizontally disposed groove 15 formed in the outer surface of a piston C, as shown in Fig. 1, and in view of the fact that said ring is continuous and has an extended bearing surface on the side wall of the cylinder D, it is leak-proof and consequently overcomes the necessity of equipping the piston with three or four packing rings as is now the universal practice in internal combustion engine construction, thereby effecting a great saving in the cost of manufacturing such engines. The ring can expand and contract without permitting the pressure in the cylinder to escape for the intermediate section B of the ring extends across all portions of the joint between the ends of the member A; nor is it possible for the pressure to leak through the joint in the intermediate member B owing to the fact that the end portions of said member are overlapped. If the groove in the piston 30 which receives the ring becomes worn to such an extent that the ring can move longitudinally of the piston, the efficiency of the ring is not impaired because it is impossible for the two sections of the ring to separate vertically. Moreover, long usage and the resultant excessive wear will not effect the ring in view of the fact that the two sections or parts of same can expand or open up quite a distance without causing the overlapping end portions of the member A and the member B to become disengaged.

From the foregoing it will be seen that I have produced a piston packing ring which

is so efficient that only one ring has to be used on a piston.

The ring can be manufactured cheaply, it can be applied and removed easily, excessive wear does not impair the efficiency of same, and it is so designed that the two parts of same cannot separate vertically in case 55 the groove in which the ring is mounted is large enough to permit the ring to move longitudinally of the piston.

Having thus described my invention, what I claim as new and desire to secure by Letters Patent is:

1. A packing ring comprising a one-piece expansible body portion, split at one point and provided with overlapping end portions, said body portion being provided in its 65 outer surface with a groove, a split expansion ring in said groove having overlapping end portions, and means for preventing said expansion ring from assuming such a position with relation to said body portion that 70 the joints between the ends of said parts a-line.

2. A packing ring comprising a one-piece ring-shaped expansible body portion split at one point by a scarf-joint, said body portion 75 being substantially channel-shape in cross section and arranged with its horizontal side legs or flanges projecting outwardly, a split expansion ring arranged between the horizontally-disposed flanges of said body portion and having overlapping end portions, and means for preventing said ring from moving circumferentially with relation to said body portion.

3. A packing ring comprising a one-piece 85 expansible body portion, split at one point, said body portion being provided in its outer surface with a groove, and a split expansion ring in said groove.

In testimony whereof I hereunto affix my 90 signature in the presence of two witnesses, this twenty third day of May 1913.

FRANK VAN DER CRUYSEN.
